(57) **CLAIM**

The ornamental design for patterned glass, as shown and described.

DESCRIPTION

FIG. 1 is a top, plan view of patterned glass showing my design;

FIG. 2 is a front elevational view thereof, the rear view being a mirror image of the front view shown;

FIG. 3 is a right side elevational view thereof, the left side view being a mirror image of the right side view shown;

FIG. 4 is a top plan view of a second embodiment of patterned glass;

FIG. 5 is a front elevational view thereof, the rear view being a mirror image of the front view shown;

FIG. 6 is a right side elevational view thereof, the left side view being a mirror image of the side view shown;

FIG. 7 is a top plan view of a third embodiment of patterned glass;

FIG. 8 is a front elevational view thereof, the rear, elevational view being a mirror image of the front view shown; and,

FIG. 9 is a right side view thereof, the left side view being a mirror image of the side view shown.
